US0D1095076S

(12) United States Design Patent (10) Patent No.: US D1,095,076 S
(45) Date of Patent:  Sep. 30, 2025

(54) BAG DISPENSER

(71) Applicant: Gina Helmick, Beach Park, IL (US)

(72) Inventor: Gina Helmick, Beach Park, IL (US)

() Term: 15 Years

(21) Appl. No.: 29/917,804

(22) Filed: Nov. 22, 2023

(51) LOC (15) Cl. 06-06

(52) U.S. Cl.

USPC D6/518

(58) Field of Classification Search
